UNITED STATES PATENT OFFICE.

ANDERS ANDERSEN PINDSTOFTE, OF FREDERIKSBERG, NEAR COPENHAGEN, DENMARK.

CARBONATOR.

1,405,323.

Specification of Letters Patent. Patented Jan. 31, 1922.

Application filed April 1, 1919. Serial No. 286,654.

To all whom it may concern:

Be it known that ANDERS ANDERSEN PINDSTOFTE, manufacturer of engines, citizen of the Kingdom of Denmark, residing at No. 5 62 Frederiksberg Allé, Frederiksberg, near Copenhagen, Denmark, has invented certain new and useful Improvements in Carbonators, of which the following is a specification.

- 10 The present invention relates to an impregnating apparatus, wherein the absorption chamber and the chamber containing the regulator are not disposed on top of one another but side by side so that, after 15 removal of the covers of the chambers, all internal parts of the absorption chamber, as well as the regulator and the like, may be removed, whereby it becomes an easy matter to clean the chambers and the parts re- 20 moved. According to the invention the absorption chamber and the chamber containing the regulator are disposed alongside of one another and, according to the invention, the two chambers are interconnected 25 partly by an air-tube at top and partly by a channel at bottom, so that the liquid will stand at the same level in the two chambers. In the said channel, there is provided a two- 30 armed lever supporting, at one end, a rod actuating the supply-valve for the liquid and, at its other end, a rod supporting the regulator. The last mentioned rod is fit- 35 tted with threads for a nut or the like on the regulator, and thereby the result is attained that the regulator connected with the nut may be raised or lowered by rotation of the rod, whereby the level of the liquid in both vessels may be varied.

The drawing shows one manner of con- 40 structing the apparatus.

Fig. 1 shows a vertical section of the apparatus and

Fig. 2 shows a horizontal section of the same.

45 The apparatus consists, in the construction shown, of an absorption chamber *b*, resting on feet *a*. The inlet to the absorption chamber is formed by a tube *c* fitted with a faucet by way of which the impregnating gas, for 50 instance carbonic acid, is introduced into the chamber *b*. At bottom in the apparatus, there is provided a tube *d* also fitted with a cock by way of which the impregnated liquid is discharged. The chamber 55 *b* is closed, at top, by a cover *f* provided with an air-discharge tube *g* fitted with a valve.

The liquid-supply tube *h* fitted with a cock passes tightly through the centre of the cover *f* and, within the chamber, it carries a sliding regulating valve *i* or the like actuated by the rod *j*, whose lower end is connected to one arm of the two-armed lever *w*, which is fulcrumed in the channel *z* and has its other arm connected to the rod *y*, supporting regulator *x*. According to the invention, 60 the regulator is located in a separate chamber *z* closed by a cover *a'*. By way of the tube *o'*, the interior of the chamber *z* communicates with the absorption chamber *b*. The cover *a'* is fitted with a stuffing box *q* 65 encircling a rotatable rod *s* fitted, at top, with handle *o* and, at bottom, with a rather long sleeve *r* formed with a polygonal socket to loosely receive the correspondingly shaped upper end of the rod *y*, so 70 that the rod may slide freely up and down in the sleeve socket, while the regulator is operating, and so that the rod *y* is nevertheless bound to follow the rotation 75 of the handle. The rod *y* is fitted with 80 threads for a nut *n* supporting the regulator so that the latter, when the rod *y* is rotated by means of the handle *o*, moves up and down in the chamber *z*, the regulator being prevented, by means of a projection *m* 85 engaged a longitudinal guide *u* fixed in the chamber *z* from following the rotary motion of the rod.

By this construction, the result is attained that the regulator *x*, as well as the entire 90 interior arrangement in the absorption chamber *b*, may easily be removed, when the apparatus is to be cleaned. A further result is that the regulator *x* may be adjusted on the rod *y*, while the apparatus is in use 95 and, thereby, the distance between the supply-valve and the surface of the liquid may be varied so that any desired degree of impregnation may be attained.

I claim as my invention:—

- 100 1. Carbonating apparatus, comprising, in combination, a carbonating chamber and a regulator chamber disposed side by side in parallel vertical relation, both chambers being closed at opposite ends; an air tube connecting said chambers at their upper ends; a channel connecting the lower ends of said chambers to balance the levels of the liquid therein, the carbonating chamber having inlets for the gas and the liquid to be treated; 110 a bodily movable valve disposed in the upper portion of the carbonating chamber and

directly associated with the liquid inlet to open and close the same; an operating rod disposed in the carbonating chamber and on the upper end of which the valve is mounted; 5 a two-armed lever fulcrumed in the connecting channel and having one arm extending into the bottom of the carbonating chamber and pivotally connected to the lower end of said rod, and its other arm extending into the bottom of the regulator chamber; a regulator disposed in the float chamber; and a rod whereon the regulator is mounted disposed in said regulator chamber and pivotally connected at its lower end 10 to the second-named arm of the lever, whereby the movements of the regulator will be communicated to, and determine the position of the valve.

2. Carbonating apparatus, comprising, in combination, a carbonating chamber and a regulator chamber disposed side by side in

parallel vertical relation, both chambers being closed at opposite ends; an air tube connecting said chambers at their upper ends; a channel connecting the lower ends of said chambers to balance the levels of the liquid therein, the carbonating chamber having inlets for the gas and the liquid to be treated; a bodily movable valve disposed in the upper portion of the carbonating chamber and 25 directly associated with the liquid inlet to open and close the same; a regulator disposed in the float chamber; and mechanical connections between the regulator and the valve for shifting the latter in accordance 30 with the rising and falling movements of the regulator to control the supply of liquid to the carbonating chamber.

In testimony whereof he affixes his signature.

ANDERS ANDERSEN FINDSTOFTE.
